UNITED STATES PATENT OFFICE.

JULIEN PERSOONS AND ALPHONSE PERSOONS, OF THILDONCK, NEAR LOUVAIN,
BELGIUM.

CENTRIFUGAL CREAM-SEPARATOR.

1,080,997.

Specification of Letters Patent.

Patented Dec. 9, 1913.

Application filed February 21, 1912. Serial No. 679,127.

To all whom it may concern:

Be it known that we, JULIEN PERSOONS and ALPHONSE PERSOONS, subjects of the King of Belgium, residing at Thildonck, near Louvain, Belgium, have invented new and useful Improvements in Centrifugal Cream-Separators, of which the following is a specification.

This invention relates to centrifugal cream separators of the type comprising a freely suspended drum.

The object of the invention is to provide an improved separator of exceptionally simple and inexpensive construction particularly suitable for small outputs.

The main feature of the improved separator according to the present invention consists in that the drum body is formed of a single piece or several permanently connected parts in such manner that it cannot be opened the liner placed within the drum being capable of collapsing to a reduced diameter in order to be introduced into the drum and of subsequently developing when in its normal working position. Owing to this feature the improved separator has all the advantages of separators in which the drum can be taken to pieces to allow of the removal or introduction of the liner, while at the same time the improved separator retains the simplicity of being in one piece.

Other features of the present invention concern the method of driving the suspension shaft of the drum, the means of guiding the said shaft, means for insuring continuous lubrication of the parts, and means for avoiding leakage from the collecting casing without recourse to an elastic joint.

These features are hereinafter described in detail and claimed.

One method of carrying out the present invention is illustrated in the accompanying drawings in which:

Figure 1 is a vertical section of the improved cream separator. Fig. 2 is a plan of the liner of the drum, shown in open or developed condition which it assumes inside the drum. Fig. 3 is a plan of the liner in collapsed condition, ready for insertion or withdrawal from the turbine. Fig. 4 is an elevational view of Fig. 3. Fig. 5 is a horizontal section on the line *a b* of Fig. 1, showing the special form of the central member of the drum. Fig. 6 is a plan and Fig. 7 a vertical section of a special key

for changing the condition of the liner at the time of its insertion or withdrawal from the drum. Fig. 8 is a horizontal section of a guide device for the suspension shaft of the drum, on the line *c d* of Fig. 9. Fig. 9 is a section of the same guide device on the line *e f* of Fig. 8.

As shown in Fig. 1 the separator comprises as usual a frame 1 having a box 2 containing the driving mechanism 3, 4, 5, 6 of known construction actuating a worm 7 formed or mounted on a hollow shaft 8 the lower end of which is supported by a ball footstep bearing 9 while its upper end rotates in a bush 10 carried by a member 11 joined to the frame 1. Through the hollow shaft 8 there passes a spindle 12 from which the drum 13 is freely suspended, the said drum having a liner 14 introduced in a manner to be described hereinafter through an opening 15. The turbine 13 is provided with a false bottom 16 to allow the separate flowing off of the cream and skimmed milk.

According to the present invention the hollow shaft 8 drives the spindle 12 through a spiral spring 18. This spring is fixed at one end to a nut 17 fixed on the upper end of the spindle 12 and surrounds the end of the hollow shaft 8. This spring 18, to a certain extent, grips the upper end of the hollow shaft 8 while its coils are wound in the opposite direction relatively to that in which the hollow shaft transmits the torque to the nut 17. Under these conditions, the coils which already grip the shaft 8 tend to decrease in diameter and increase their grip whenever any torque is transmitted to the spring. On the other hand if rotation occurs in the opposite direction or on the arising of a resistance acting in the opposite direction to the driving torque, the coils of the spring tend to open and uncouple the hollow shaft from the rod 12.

The rod 12 from which the drum is suspended requires as usual to be guided below the ball bearing. The guiding means employed in connection with the present invention consists of four pins 19 pressing against the circumference of the spindle 12 and lodged in a cup member 20; these pins terminate near the outer periphery of the cup member 20 in conical surfaces 20' which are surrounded by four metal wires 21 wrapped about the cup member 20. The guide device thus formed is attached by a bolt not illus-

trated, in the space 22 in the frame 2. It is readily understood that owing to this arrangement the guide device has a progressively increasing action. The oscillations of the rod 12 are transmitted to the pins 19 which tend to be displaced horizontally in the grooves of the cup member 20 in which they are lodged. Owing to the conical form of the external surface 20' of the pins 19, these latter begin to act on the lowest wire 21 and according as the amplitude of the swings of the spindle 12 increases, the surfaces 20' successively act on two, three, or four wires, so that the resistance to the swings of the spindle 12 appreciably increases with the amplitude of the said swings.

In the lower part of the space 22 is screwed a metal plug piece 23 for insuring tightness at this part of the frame owing to the provision of an elastic joint 24. The lubricant is thus prevented from attaining the collecting casing 26. The space 22 communicates through a hole 25 with the box 2 of the frame so as to return thereto the lubricant which collects in the space 22 owing to the movement of the mechanism. This arrangement insures perfect and continuous lubrication owing to the constant oil circulation during the operation of the separator.

Within the casing 26 which will be afterward more fully described, is located the drum proper 13 which has the following features: The drum is formed of two pieces, preferably beaten or stamped out, these pieces being permanently connected to each other. It is united to an upper plate 35 provided with an opening 36 for the milk supply. Through this opening passes the lower end of the spindle 12 which is hooked to a ring or hook 37 attached to a central hub 38 to which is screwed or otherwise attached the drum body. As this drum body is not adapted to be opened for the introduction of the liner 14, this latter is made of special construction so as to be capable of insertion through the lower opening 15 of the false bottom lodged in the lower opening 39 of the drum body. The liner 14 is shown separately in Figs. 2, 3 and 4 and comprises a certain number of blades 40 each fixed to a vertical rod 41. These rods are held by a ring 42 lodged in an opening 43 provided in the central part of the blades. These latter are formed with recesses 44 and 45 so as to conform to the internal shape of the drum and to enable pins 33 carried by a special key 32 to be introduced between the blades for a purpose to be subsequently described. When the blades 40 of the liner are turned down on to one another the liner assumes the form shown in Figs. 3 and 4, its diameter being then less than the internal diameter of the opening 15 of the false bottom 16 so that the liner as a whole can be introduced into

the drum. Then by introducing the pins 33 of the key 32 between the blades 40 in the manner shown in Fig. 3, the blades can be rotated so as to cause the liner to assume the open or developed condition shown in Fig. 2, if at this instant the rods 41 are prevented from turning about the central member 38 supporting the drum. This result is obtained by providing this central member 38 with a certain number of flutings 46 on its external surface, in which flutings the rods 41 lodge when the liner is put in place. On the other hand when the liner 14 is to be withdrawn from the turbine 13 it is only necessary to turn the key 32 in the reverse direction so that the pins 33 inserted between the blades 40 turn these blades in toward the center to occupy the position shown in Fig. 3. The liner can then be inserted in and withdrawn from the drum as required, for cleaning or other purposes, although the drum cannot be taken apart and consists either of a single piece or of several pieces permanently connected to each other. The false bottom 16 should obviously be introduced into the drum body in course of construction. This false bottom can be easily cleaned since after removal of the liner 14 it may be pushed to the top of the drum in order to clean its lower surface and the lower conical surface of the drum body. The upper surface of the false bottom may be cleaned by inserting the hand in the drum body through the opening 15.

The upper part of the drum body is provided with openings 47 for the passage of the milk and the lower part is provided with openings 48 through which the skimmed milk flows away. The cream collects in a receiver 31 and the skim milk in a receiver 30 these receivers being formed in the collecting casing 29. This latter comprises an upper part 26 integral with the frame 1 and a lower part 29 preferably of sheet metal, simply attached by hooks to the upper part. The upper part is provided with two edges 27 and 28 one of which 28 projects a certain distance into the lower part 29 and is preferably given a certain inclination; under these conditions no leakage is possible between the two parts, while no joint is required.

The construction hereinbefore described has the following important advantages over existing separators: It has the advantage over drums made of two or more parts of not experiencing wear and tear, having no screws or bolts and never being taken to pieces; at the same time its manipulation is much simpler and easier requiring no joint to prevent leaking and being always ready for use after cleaning. In addition to these advantages it has a much higher efficiency proportional to its bulk than drums in one piece without liner, and this without the op-

eration of cleaning becoming troublesome, since the liner can be easily removed from the drum when required, as has already been explained.

5 The device for driving the shaft has the advantage of great simplicity while at the same time it constitutes a clutch which is particularly flexible and capable of running freely whenever the mechanism becomes 10 jammed for any reason, thereby avoiding accidents.

The improved guide device has the advantage already pointed out of progressive action while at the same time it is extremely 15 reliable; being located in the lubrication circuit it shares the advantages of continuous automatic lubrication.

The frame 1 may be provided in the box 2 with a space 49 for collecting the impurities 20 contained in the oil or other lubricant; this enables foreign matters contained in the lubricant to be withdrawn from the circulation, and prevents such matters from being constantly brought in contact with the moving 25 parts.

Having thus described our invention, what we claim is:

1. In a centrifugal cream separator, a hollow drum substantially circular in cross-section, said drum being provided with an 30 opening of less diameter than the diameter of the drum, a collapsible liner adapted for insertion in and removal from said drum

through said opening in its collapsed position.

35

2. In a centrifugal cream separator, a hollow drum substantially circular in cross-section, having an opening therein of less diameter than the diameter of the drum, a collapsible liner comprising a plurality of 40 rotatably mounted blades adapted for insertion and removal through said opening in its collapsed position, and means for positively rotating the blades of said liner to their operating position when in the drum. 45

3. In a centrifugal cream separator, a hollow drum substantially circular in cross-section having an opening therein of less diameter than the diameter of the drum, a collapsible liner adapted for insertion and 50 removal through said opening, said liner comprising a plurality of rotatably mounted blades, means for preventing relative concentric rotation of the liner and drum, and means for positively rotating the blades to 55 their operating position when the liner is in place in said drum.

In testimony whereof we have signed our names to this specification in the presence of two subscribing witnesses.

JULIEN PERSOONS.
ALPHONSE PERSOONS.
